UNITED STATES PATENT OFFICE.

JERRY LEWIS, OF LITTLE ROCK, ARKANSAS.

BURNER-CONTROLLING MECHANISM.

1,252,707.

Specification of Letters Patent. Patented Jan. 8, 1913.

Application filed November 29, 1912. Serial No. 134,217.

To all whom it may concern:

Be it known that I, JERRY LEWIS, a citizen of the United States, residing at Little Rock, in the county of Pulaski, State of Arkansas, have invented certain new and useful Improvements in Burner-Controlling Mechanism, of which the following is a description, reference being had to the accompanying drawings, forming a part hereof.

10 The object of the invention is to provide a simple, relatively inexpensive and efficient mechanism adapted to be applied as an attachment to any ordinary valve head of standard type and having means whereby 15 a relative and regulable supply of gas or other fluid fuel and air or other combustion supporting agent may be supplied either automatically, under the control, for example, of steam pressure as when the device is used in 20 connection with a steam boiler furnace, or manually and, if preferred, the adjustment of the mechanism to vary the relations of supply between the fuel and the combustion supporting agent and to provide for either 25 automatic or manual operation, may be effected with facility.

Further objects and advantages of the invention will appear in the following description of a preferred embodiment, it being understood that changes in the form, proportion and minor details may be resorted to within the scope of the appended claims without departing from the spirit of the invention.

35 In the drawings,

Figure 1 is an elevation partly in section of a mechanism showing one embodiment of the invention.

Fig. 2 is an elevation of the same viewing 40 the mechanism in a plane at right angles to that of Fig. 1.

Fig. 3 is a plan view.

Fig. 4 is a plan view showing an adjustment of the mechanism adapting it for manual operation.

Fig. 5 is an elevation of the upper portion of the mechanism as shown in Fig. 4.

Fig. 6 is a detail sectional view showing the fuel control valve.

50 In the illustrated mechanism, the head 10 may be of the ordinary or well known construction provided with a fuel controlling valve 11 and a nozzle or feed pipe 12 which may be terminally supported in any 55 convenient manner as by means of a spider having a hub 13 in which the nozzle is seated

and arms 14 supporting the same in proper relation to the fuel opening 15 of the furnace, said fuel opening being shown of conical or inwardly tapered form to provide for 60 a graduated control of the air inlet formed by the space between the fuel nozzle and the opening in the furnace wall for co-operation with an air cut-off consisting of a disk 16 which is slidably mounted upon said nozzle 65 or feed pipe 12.

Connecting the axis 17 of the fuel valve with the air cut-off disk is a crank 18 and a link 19, whereby as the fuel valve is turned to increase or diminish the flow of fuel, the 70 air cut-off disk is moved outwardly or inwardly with reference to the air supply space to vary the admission of air proportionately to that of the fuel. The actuation of the fuel valve may be accomplished manually as 75 through the agency of a handle or lever 20 connected in any suitable manner with the spindle of the fuel valve, or automatically under the influence of steam pressure in the boiler when the mechanism is used in connection with a steam boiler furnace, a steam connection 21 being established between the steam boiler (not shown) and a cylinder 22 secured as by a clip 23 or an equivalent thereof to the valve head and containing a 80 piston 24 carried by a stem 25 which is weighted as at 26 to provide for the depression of the piston and stem when the steam pressure below the former decreases.

The connection between the piston stem 90 and the fuel feed valve consists essentially of a rack 27 carried by the stem and engaging a segment 28 secured to the valve and preferably formed as a part of the crank arm 18, an adjustable connection being established between said segment or crank arm element and the valve. A handle 95 20 may be secured by means of a set screw 29 engaging a slot 30 to provide for varying the relation between the fuel valve and 100 the air cut-off disk to secure a relative supply of fuel and air or other combustion supporting agent which will result in the most effective and economical combustion of the fuel.

In the construction illustrated, the rack 27 is formed as an extension, (either integral or otherwise rigid) of the stem 25 and passes through a guide 31, said rack being flexible and the guide being of sufficient 110 dimensions to permit of the flexing of the rack, as indicated by the dotted lines in Fig.

5, to disengage the teeth of the rack from those of the segment, and pivotally mounted on the guide and coöperating therewith is a holding element 32 which when in the 10 position indicated in Fig. 1 holds the rack with its teeth in positive engagement with those of the segment. Said holding element is pivotally mounted to permit of its being deflected, as shown in Fig. 4, to allow 15 of the disengagement of the rack from the segment and when this disengagement has been effected, the valve coupling with its attached operating arm 20 and segment and connection between the segment and the air 20 control disk may be turned to the position indicated in Figs. 4 and 5 to provide for a manual adjustment of the fuel and air supply. To facilitate the relative adjustment of the rack and segment, the upper end of 25 the former may be provided with a butterfly finger hold 33. Also to permit of drainage of the cylinder, a valve outlet 34 may be provided.

In practice a relative adjustment of the 25 crank arm 18 and the valve 11, through the agency of the set screw 29 and slot 30 should be effected to secure a supply of air proportioned to the supply of fuel to obtain a flame indicating complete combustion, after 30 which the rack may be engaged with the segment with the fuel and air control elements in position to supply the fuel and air in the required volume to maintain the necessary temperature or steam pressure in the 35 boiler, after which any reduction of the steam pressure will result, through the decrease of pressure in the lower end of the cylinder 22 and the effect of the weight 26, in depressing the piston stem and the increase in the supply of fuel and combustion 40 supporting agent; whereas an increase in the boiler steam pressure will result in the cutting off in part of the fuel and the air supply, to the end that a normal and uniform 45 pressure of steam in the boiler may be maintained automatically.

What I claim is:—

1. The combination with a fuel supply valve and a cut-off for combustion supporting agent, of operating connections between 50 said elements for securing proportional

movement thereof, and means for operating the valve including a toothed segment secured thereto, a rack for engagement with said segment, manually displaceable means 55 for normally holding the rack in engagement with the segment, and steam pressure actuated means for operating the rack.

2. The combination with a fuel supply valve and a cut-off for combustion supporting agent, of operating connections between 60 said elements for securing proportional movement thereof, and means for actuating the valve including a toothed segment secured thereto, a displaceable rack for engagement with said segment, a manually operated movable holder for maintaining the rack normal in engagement with the segment, and steam pressure actuated devices 65 for operating the rack.

3. The combination with a fuel supply valve and a cut-off for combustion supporting agent, of operating connections between 70 said elements for securing proportional movement thereof, and means for actuating 75 the valve including a toothed segment secured thereto, a rack for engagement with the segment, a guide for the rack in which the latter is movable for disengagement from the segment, a manually operated pivotal rack holder for normally retaining the rack in engagement with the segment, and steam pressure controlled devices for actuating the segment.

4. The combination with a fuel supply 80 valve and a cut-off for combustion supporting agent, of operating connections between said elements for securing proportional movement thereof, and means for actuating the valve including a segment carried 85 thereby, a rack for engagement with the segment, a piston exposed to boiler steam pressure and having a stem carrying said rack, and manually operated removable means for normally maintaining the rack 90 in engagement with the segment.

This specification signed and witnessed this 24th day of November, A. D. 1916.

JERRY LEWIS.
